INVENTOR.

James A. Ross,

BY

Geo. Kimmel, ATTORNEY.

UNITED STATES PATENT OFFICE.

JAMES A. ROSS, OF NORTH TONAWANDA, NEW YORK.

HOT-AIR DISTRIBUTOR.

Application filed December 22, 1926. Serial No. 156,393.

This invention relates to a hot air distributor designed primarily for use in connection with pipeless furnaces, but it is to be understood that a distributor, in accordance with this invention can be used in any connection with which it is found applicable, and the invention has for its object to provide, in a manner as hereinafter set forth, a distributor for positioning over a hot air outlet for deflecting the warm air out into a room or hallway and keeping it in circulation nearer the floor thus effecting more complete utilization of heat from the furnace or source of supply, and further by its use, resulting in a saving of fuel consumption.

A further object of the invention is to provide, in a manner as hereinafter set forth, a hot air distributor capable of being employed, when deflecting the heat, as a foot warmer.

Further objects of the invention are to provide, in a manner as hereinafter set forth, a hot air distributor which is simple in its construction and arrangement, strong, durable, compact, thoroughly efficient in its use, conveniently installed with respect to a hot air outlet, and comparatively inexpensive to manufacture.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a hot air distributor, in accordance with this invention, showing the adaptation thereof in connection with the hot air outlet of a pipeless furnace.

Figure 2 is a vertical sectional view of the distributor, showing the adaptation thereof with respect to the hot air outlet of a pipeless furnace.

Figure 3 is a fragmentary view, in vertical section, of a modified arrangement of top plate.

Referring to the drawings in detail 1 denotes a floor, mounted on joists 2, and provided with an opening 3. The joists 2 project inwardly from the wall of the opening 3 to form a seat 4 for a purpose to be presently referred to. Vertical supports 5 are secured to the joists 2. As illustrated the opening 3 is of square contour and mounted upon the seat 4 and snugly abutting against the wall of the opening 3 is a grating or register 6. The grating 6 is flush with the upper face of the floor 1.

A hot air duct is indicated at 7 and which leads from a pipeless furnace or other suitable source of hot air supply. The duct 7 is cylindrical in cross section and the diameter thereof is less than the width and breadth of the grating 6. The top edge of the duct 7 abuts against the lower face of the grating 6 and said duct 7 is disposed centrally with respect to said grating 6. The diameter of the ducts 7, with respect to the width of the grating 6 is such, that when the duct 7 is positioned relatively to the grating 6, the latter will be provided with a hot air outlet portion 8 and a cold air inlet portion 9, which is arranged exteriorly with respect to the outer periphery of the wall of the duct 7. The outer periphery of the wall of the duct 7 is positioned a substantial distance from the end edges of the inwardly projecting portions of the joist 2.

The distributor comprises an inverted hollow frusto-conical body portion 10 having an inlet 11 at its lower end and its upper end closed by a flanged top plate 12. The body portion 10 in proximity to each top edge is formed with spaced ports 13. Formed integral with the lower end of the body portion 10, as well as communicating with the inlet 11, is the upper stationary section 14 of a tubular neck, and the latter further includes a lower shiftable tubular section 15 which is slidably mounted on the section 14. The section 15 has a bayonet shaped slot 16 through which extends a pin 17 carried by the lower end of the section 14. The body portion 10 is a deflector.

The body portion 10 is supported in a vertical position, by a series of spaced legs 18 and each of which is formed with a foot 19. Each leg consists of a vertically disposed bar 20 having an out-turned upper end 21 which is fixedly secured to the body portion

10, by the holdfast device 22, at a point removed from the top edge of said body portion 10. Associated with each leg 18 is a brace member 23 which is formed with a pair of angularly disposed end portions 24, 25. The end portion 24 is secured to the body portion 10 by the hold fast device 26, and the end portion 25 is secured to the lower end of the bar 20 by the holdfast device 27. The 10 top plate 12 is provided, axially thereof, with a handle 28 preferably constructed of wood.

When the distributor is mounted in the position as shown in Figure 2, it will serve to 15 deflect the warm air out into the room and keep it in circulation nearer the floor, thus effecting more complete utilization of the heat from the furnace. As the neck portion 20 is hollow, the warm air can enter the body portion 10 in sufficient quantity to thoroughly heat it and the distributor can then operate as a foot warmer, at the same time performing its deflecting action. The ports 13 at the upper end of the body portion 10 permit 25 of the hot air which enters the body portion to be discharged therefrom, thereby insuring a steady flow of heat through the body portion 10.

The tubular neck provides means for 30 positioning the distributor with respect to the grating 6. The distributor preferably will be positioned centrally with respect to the grating, as such position would obtain maximum results. The setting up of the neck 35 with the lower shiftable section 15, enables said section to be slid up higher than the feet of the supporting legs, enabling the user of the device to place the distributor in any desired position on the register and after so 40 positioned, the lower section is moved downwardly to extend through an opening in the grating and which prevents the shifting of the distributor relative to the grating.

The handle, which preferably is constructed 45 of wood, insures a cool hold at all times, when it is desired to remove the device from its position on the grating. It is to be noted that the device is of compact enough construction so it can be easily removed entirely, 50 if and when desired. The supporting legs are of suitable design and are placed and riveted to the body portion 10, and which insures solidity of the device when placed on the floor and insures proper equilibrium at 55 all times. The distributor can be constructed of any suitable metallic material, polished or unpolished and can be of any desirable size.

The distributor will keep the warm air 60 from going directly upward, but instead diffused more evenly throughout the room. The distributor diffuses the warm air in a substantially horizontal direction throughout the immediate room, as well as into an adjoining room and the angle of deflection

can be any desired, but preferably it is forty-five degrees.

The device can be utilized as a compact foot warmer by placing one's feet on the top plate 12, far enough from the floor, so that the cool air return draft will not interfere. Furthermore the use of the distributor will provide for a saving in fuel consumption and also it is of a simple and steady construction and easily moved about.

In the modified form shown in Figure 3, the top plate indicated 28 is of such diameter with respect to the upper end of the hollow frusto-conical body portion 29 to project laterally therefrom and form a warm air deflecting portion 30. The marginal part of the top plate 28 is bent upon itself to form a fold 31 and a flaring flange 32. The upper end of the body portion 29 is surrounded by the flange 32 and the latter being positioned inwardly with respect to the bend 33, which provides the edge of the plate 28. The portion 30 aids in deflecting the warm air into the room nearer the floor. The portion 30 surrounds the upper end of the body portion 29. Otherwise than that as stated, the form illustrated in Figure 3 will be the same, as that set forth by Figures 1 and 2.

It is thought the many advantages of a hot air distributor, in accordance with this invention, can be readily understood, and although the preferred embodiment of the invention is as illustrated and described, yet it is to be understood that changes in the details of construction can be had which will fall within the scope of the invention as claimed.

What I claim is:

1. A hot air distributor for the outlet of a hot air flue comprising an inverted frusto-conical hollow deflector member closed at its top and open at its lower end, means secured to said element for supporting it in superposed spaced relation with respect to said outlet, said member in proximity to its top provided with outlet ports, and a tubular retaining element depending from and connected to the lower end of said member, said element opening into said member and being of a length to extend into said flue.

2. A hot air distributor constructed in accordance with claim 1, wherein said element consists of a stationary upper section and a shiftable lower section slidably connected to the upper section.

3. A hot air distributor for the outlet of a hot air flue comprising an inverted frusto-conical deflector member, a plurality of vertical disposed spaced supports connected to and providing means for supporting said member in superposed spaced relation with respect to said outlet, and a retaining element secured to and depending from the lower end of said member and of a length to extend into said flue.

4. A hot air distributor constructed in accordance with claim 3, said element consisting of a stationary upper section and a shiftable lower section slidably connected to the upper section.

5. A hot air distributor constructed in accordance with claim 3, said deflector mem-

ber being hollow, closed at its top, open at its lower end and formed with discharge ports, said element being tubular and opening into the lower end of said member. 10

In testimony whereof, I affix my signature hereto.

JAMES A. ROSS.
